UNITED STATES PATENT OFFICE.

FRANK S. WEISE, OF BALTIMORE, MARYLAND.

PRINTING-MACHINE.

1,305,849.

Specification of Letters Patent. Patented June 3, 1919.

Application filed January 30, 1919. Serial No. 273,983.

To all whom it may concern:

Be it known that I, FRANK S. WEISE, a citizen of the United States, residing at Baltimore, in the State of Maryland, have 5 invented certain new and useful Improvements in Printing-Machines, of which the following is a specification.

This invention relates generally to printing machines and more particularly to an 10 apparatus for canceling checks, bills, invoices, coupons, and similar papers.

The primary object of the invention is to provide an improved mechanism for actuating 15 a type carrying device so that the type will successively engage a platen and ink pad during operation of the mechanism.

The invention further contemplates the provision of an improved mechanism for printing apparatus adapted to be associated 20 with an adding machine whereby the printing mechanism may be actuated simultaneously when the adding machine is actuated so that the checks, bills and other papers will be successively stamped and canceled 25 during operation of the adding machine.

Another object of the invention is to provide a printing machine having a type carrying mechanism arranged to operate substantially vertically toward and away from 30 its platen thereby avoiding a swinging, fanning action which tends to create gusts of wind and consequent disarrangement of the papers to be printed.

The invention further aims to provide a 35 printing apparatus which will include a type carrying mechanism having a combined swinging and reciprocatory motion accomplished by a simple arrangement of gearing and interlocking parts all of which may be 40 actuated by a relatively short oscillatory movement to a drive shaft so that the type or die is alternately engaged with both the platen and ink pad.

The above and additional objects are accomplished 45 by such means as are illustrated in the preferred embodiment and in the accompanying drawings, wherein like characters denote like or corresponding parts throughout the several views, in which:—

50 Figure 1 is a perspective view of the apparatus showing its application to an adding machine,

Fig. 2 is a side elevation, partly in section, showing the apparatus in inoperative position 55 in full lines, and in operative printing position in dotted lines.

Fig. 3 is a rear elevation.

Fig. 4 is a front elevation showing the mechanism in operative printing position.

Fig. 5 is a section taken on the line 5—5 60 of Fig. 4.

Fig. 6 is a vertical section through the machine taken approximately on the line 6—6 of Fig. 3 but showing the mechanism partially moved from inoperative position. 65

Fig. 7 is a perspective view of the type carrying device, showing the type plate partially removed.

Fig. 8 is a detail view of the operating 70 crank.

Fig. 9 is a detail view of the ink pad actuating mechanism.

Referring to the drawings, wherein is illustrated the preferred form of my invention, in which like numerals of reference indicate like or corresponding parts throughout the several views, the frame of the machine comprises the base plate 1 and the upright side plates 2 and 3 fixed to the base plate in any preferred manner and each 75 provided with vertical front edges 4 and inclined top edges 5 to which is secured a removable cover 6 held in position by suitable fastening screws 7 and which, together with the side plates forms a casing for protecting 80 the mechanism mounted between the side plates 2 and 3. A suitable platen 8 is mounted upon the base plate 1.

The end of the drive shaft 9 is journaled in suitable bearings in the side walls 2 and 3 and a counter shaft 10, parallel to the drive shaft 9, also has its ends journaled in suitable bearings in the side walls. Both of these shafts extend transversely across the space between the side walls and carry the 95 gears by which the proper motion is transmitted to the printing member or die.

Segmental gears 11 are mounted on the counter shaft 10 near the side walls 2 and 3 and are rigidly fixed to the shaft to turn 100 therewith. The drive shaft 9 is also provided with a segmental gear 12, the teeth of which mesh with a pinion 13 on the counter shaft 10. In this manner movement is imparted to the segmental gears 11 when the drive shaft 9 is actuated. A supporting shaft 14' is mounted at the top of the frame, the ends of the shaft being journaled in suitable bearings arranged at the top of the side plates 2 and 3, and guide rods 14 are 105 suspended from the shaft 13 by having their upper ends fixed to the shaft so that the

rods will readily swing as the shaft turns in its bearings. Sleeves 15 are slidably mounted upon the guide rods 14 and are adapted to be longitudinally moved thereon. Each 5 sleeve has integrally formed therewith, or otherwise secured thereto, an elongated plate or relatively wide bar 16 the ends of which are rounded as shown to advantage in Figs. 6 and 7. A series of rods 17 have their ends 10 fixed to the bars 16 and are equally spaced apart, the rods serving as the teeth of a rack adapted to be engaged by the segmental gears 11. In this connection it should be borne in mind that an ordinary rack bar 15 may be mounted on each member 16 if desired, the rods 17 in this case being dispensed with.

The lower ends of the bars 16 have attached thereto the disks 18, each of which 20 has an annular flange 19 cut out as at 20 to form a gap through which the lower end of the corresponding bar 16 is extended as shown to advantage in Figs. 6 and 7. The lower rounded ends of the bars, extended 25 into spaces embraced by the flange 19, therefore, form the inner edges of the arcuate grooves 21, the purpose of which will presently appear. The flange 19 in each disk, is also notched as at 22 forming an opening 30 which serves as an entrance to the groove 21 in each disk.

Each segmental gear 11 carries a pin 23 so located on the side of the segmental gear as to cause it to be received in the groove 21 35 of the adjacent disk 18, through the entrance 22 thereof, when the mechanism is in operation.

A brace rod 24 extends between the upper ends of the members 16. A type carrying 40 element is secured to the rods 17 and the same consists of a plate 25 having ears 26 arranged in pairs and adapted to embrace the lowermost of the series of rods 17. A removable fastening element 27, arranged in 45 each pair of ears 26, is extended through the space between two of the rods 17 so that the plate 25 is held rigidly in position. Parallel grooves 28 are formed on the bottom of the plate 25 and these grooves are adapted 50 to receive a removable die plate 29, which carries the type 30. A spring latch 31 is attached to the plate 29 and has its hooked end 32 adapted to engage the lowermost of the rods 17 so that the plate 29 is held 55 against accidental or casual displacement from the plate 25 when the type is in position.

The sleeves 15 mounted upon the guide rods 14, and carrying the rods 17 and bars 60 16, therefore, provide a carriage, movable on the guide rods 14 for carrying the stamping or printing device during actuation of the mechanism.

At the rear of the base plate is a standard 65 33 upon which an ink pad 34 is mounted, the

latter being preferably held at an angle as shown. The ink pad 34 is of circular formation and is rotatably mounted upon the stem 34' as shown to advantage in Fig. 5 of the drawing so that the ink pad may be readily turned. An annular flange is formed on the ink pad and this is provided with a series of teeth 45 on its lower surface. The drive shaft 9 is provided with a collar 46 held by a set screw 47 and this collar carries ears 48 through which a pivot pin 49 is extended. A spring pressed pawl 50 is mounted on the pin 49 and is disposed so that its end engages the teeth 45, this structure being shown to advantage in Figs. 3 70 and 9 of the drawings. When the shaft 9 is actuated in one direction, a rotary motion will be imparted to the rotatably mounted pad. When the shaft 9 returns to normal 75 position, however, the pawl will ride over the teeth and therefore it will be obvious that the pad will be rotated only in one direction.

One end of the drive shaft 9 is extended beyond one of the side walls as indicated 80 at 35 and has its terminal provided with a hand crank 36. A coil spring 37 has one end fixed to the shaft as indicated at 38 and the opposite end of the spring is engaged with the side walls 3 of the frame. The 85 spring 37 exerts a pressure on the shaft so that the type is normally held in engagement with the ink pad.

Referring to Fig. 1 wherein the device is shown mounted upon an adding machine, 90 the crank 36 is shown connected to a pitman 39 by a removable pin 36' and is fixed to a lever 40 included in the adding machine mechanism. It will be obvious therefore, that the printing machine will be actuated 95 upon each actuation of the adding machine lever 41.

The crank 36 as shown to advantage in Fig. 8, consists of two hingedly connected parts 51 and 52, the part 52 having a flat 100 spring fixedly connected by the fastening element 53 while the opposite end of the flat spring bears against the part 51. This spring is comparatively stiff so that there will be no pivotal action of the parts until 115 some resistance, in addition to that offered by the mechanism is encountered. The purpose of this will hereinafter appear.

Assuming that a stack of checks, bills, invoices, coupons or other papers is placed 120 upon the platen 8. When the figures indicated on the uppermost paper are recorded on the adding machine the operator will actuate the operating handle 41 whereupon the shaft 9 will be actuated through the 125 connected members 36, 39 and 40. Approximately a quarter turn will thereby be given to the shaft 9 and consequently to the segmental gear 12 which by virtue of its meshing with the pinion 13, will cause the counter 130

shaft 10 to turn and thereby actuate the segmental gears 11. Fig. 5 clearly illustrates the engagement of the segmental gears 11 with the rods 17 and it will be apparent that the type carriage will be actuated when these gears 11 are actuated. There are as many rods 17 as there are teeth in the segmental gears 11 so that the lowermost rod 17 will engage one of the end teeth in each segmental gear 11. The gears 11 will thereby swing the lower end of the carriage forwardly and upwardly until the carriage is in vertical position above the platen. Continued movement causes the carriage to move downwardly vertically toward the platen to engage the latter or any papers placed thereon. The rods 14 swing from the shaft 13 and the carriage slides on the rods so that there is a combined swinging and vertical movement given to the carriage as it moves from the ink pad to the platen.

As soon as the operator releases the adding machine lever 41, the spring 37 will urge the shaft backwardly whereupon the parts will return through the reverse movement until the type is engaged with the ink pad. While the parts are in the latter position the pins 23 on the segmental gears 11 are in registration with the grooves 21 as shown by dotted lines in Fig. 2. As the segmental gears 11 are swung, the pins 23 travel through the grooves 21 and the proper relative positions of the carriage and segmental gears 11 are thereby maintained so that the rods 17 are held in mesh with the teeth on the segmental gears. Continued movement of the mechanism causes the pins to reach the ends of the grooves 21 and the pins disengage the disks by passing out through the open ends 22 of the grooves. The carriage then continues downwardly vertically until the type engages the papers to be printed. After the pins pass out of the grooves 21, outward swinging movement of the carriage is prevented by virtue of its engagement with the front portion of the cover 6 as shown in Fig. 5 of the drawing.

When the stack of papers is of considerable height it will be obvious that the printing plate must stop during its downward movement toward the platen. Therefore the crank 36 is constructed of the two hinged parts 51 and 52 as above stated so that the resistance offered by the stack of papers, while it will cause the mechanism to stop, will not prevent the continued movement of the portion 51 of the crank as shown by dotted lines in Fig. 8. Therefore, the pitman 39 may move through its full movement upon each actuation of the adding machine and the movement of the printing plate will be governed entirely by the height of the stack of papers on the platen.

It is possible, of course, to operate the

mechanism by applying the power directly to the counter shaft 10 and when the machine is used for ordinary printing purposes, not in conjunction with an adding machine or the like, it will be found advisable to apply the power directly to the shaft 10. By using the power shaft 9, with its crank, and the relatively large segmental gear 12, sufficient leverage is obtained whereby the limited movement of the lever 40 on the adding machine, is sufficient to actuate the crank through a quarter turn for imparting the desired movement to the mechanism. Fig. 3 shows the application of a motor 42 to the device, the motor shaft 43 being extended into a housing 44 within which a suitable connection is made with the shaft so that the latter will be actuated when the printing machine is used for ordinary printing purposes. When electricity is employed to actuate the machine, it will be obvious that other electrical devices, such as solenoid, induction coils or the like, may be employed to actuate the power shaft.

The motion of the carriage, it will be observed is a combined swinging and reciprocating movement which causes the type plate to move from the elevated angularly disposed ink pad outwardly and vertically downwardly toward the platen. The swinging fan like motion, commonly employed on some check canceling devices, therefore, is avoided and consequently no gusts of wind will be created nor will a shifting of the papers take place and the papers, arranged in a stack on the platen, will not be disarranged and the machine may be rapidly operated while no device for holding the stacks of papers is required.

The base plate 1 is hingedly mounted by means of the hinge 54 to the rear edge of the adding machine shelf. By this construction it is possible, after removing the removable pin 36' to swing the entire device off the shelf and permit the same to hang down below the shelf at the rear thereof so that the shelf may be entirely clear when it is not desired to use the printing apparatus. Removable fastening elements 55, attached to the front edge of the base plate, and extending through convenient openings in the shelf of the adding machine are employed to maintain the apparatus in firm position on the shelf when the apparatus is in use.

The vertical movement of the type prevents the tendency of the stack of checks to shift and topple and also prevents blurring when the checks are printed. Furthermore, the position of the platen in front of the mechanism permits the checks to be in sight of the operator at all times. The inking pad protected by the cover and successively engaged by the type will prevent excessive ink being supplied to the type and consequently

the printed impression will not be unduly wet.

It should be pointed out that the machine is adapted to be connected up in series by placing several of the machines side by side, or front to back and having the shafts 9 extended and coupled together so that all of the machines in the series will simultaneously operate. This will be found useful in 10 post-offices, banks and mercantile establishments where large quantities of papers are to be canceled. A sheet or a stack of sheets may be placed on each machine and therefore several papers may be canceled at the 15 same time.

The platen 8 is preferably slidably mounted in a dovetailed groove 56 and its marginal edges are shaped to fit in the groove so that lateral sliding movement of the platen 20 on the plate 1 is permitted. A finger depression 57 in the platen permits the operator to slide the plate. This will permit the checks to be shifted so that the canceling stamp may be applied to any part of the 25 surface, as it will be understood that the checks will be received at the bank with one or more prior cancellations and it is desirable that the cancellation marks be separate and legible. The checks may be readily 30 shifted when in a stack by merely moving the platen.

The foregoing description and accompanying drawings have reference to what might be considered to be the approved or 35 preferred form of my invention. I desire it to be understood that I may make such changes in the construction, combination and arrangement of parts, materials, dimensions, et cetera as may prove expedient and 40 fall within the scope of the appended claims.

Having thus fully described my invention what I claim as new and desire to secure by Letters Patent, is:—

45 1. A printing machine comprising a drive shaft, a type carrying carriage swingingly and slidably mounted, and means mounted on the shaft and on the said carriage to transmit swinging and sliding movement 50 to the carriage when the said shaft is actuated.

55 2. A printing machine comprising a drive shaft, a type carrying carriage adapted for lateral swinging and vertical reciprocating movement, and means mounted on the shaft and on the said carriage to laterally swing and vertically reciprocate the carriage when the said shaft is oscillated.

60 3. A printing machine comprising parallel guide rods suspended for free swinging movement, and a type carrying carriage, mounted for longitudinal sliding movement on said guide rods, and adapted to swing with said guide rods during its 65 sliding movement thereon.

4. A printing machine comprising parallel guide rods suspended for free swinging movement, a type carrying carriage having parallel bars, each disposed adjacent one of said parallel guide rods, means for slidably connecting said bars to said guide rods to permit sliding movement of the carriage on the said guide rods. 70

5. A printing machine comprising parallel guide rods suspended for free swinging movement and disposed in spaced relation, a type carrying carriage having laterally spaced parallel bars equipped with sleeves to receive the said guide rods at opposite sides of the said carriage to permit 80 sliding movement of the carriage on the rods and swinging movement therewith when the carriage is actuated.

6. A printing machine comprising supports, a carriage swingingly suspended 85 from said supports and adapted for vertical sliding movement, gearing mounted on the support and engageable with the carriage to swing the latter, means for retaining the gearing and carriage in relative 90 operative position during swinging movement of the carriage, and means engageable with the carriage to maintain the latter in vertical position when the said first mentioned means is disengaged at the end of 95 the said swinging movement of the carriage.

7. A printing machine comprising supports, a carriage suspended from the supports and adapted for swinging and vertical sliding movement, a shaft journaled in 100 the said supports and carrying gears engageable with the carriage to swing the latter, the said gears having projecting pins, the said carriage having arcuate grooves to receive the said pins during swinging 105 movement of the carriage when the said gears are actuated, and means to maintain the carriage in a vertical position at the end of the swinging movement thereof, and during continued actuation of the said gears 110 when the said pins are out of registration with the said grooves.

8. In a printing machine, the combination with a type plate, a platen, and an elevated ink pad, a movable carriage, having 115 transverse parallel rods, a shaft rotatably mounted and carrying segmental gears, having teeth equal in number to the said rods and engageable therewith, the said carriage being swingingly mounted above 120 the platen and adapted to swing from the said pad to a vertical position above the platen, the lowermost rod being engageable with one of the end teeth in each segmental gear, whereby the said carriage is 125 swung when the said segmental gears are actuated by the shaft, the said carriage being vertically movable toward and away from the said platen when the said teeth are in mesh with the said rods. 130

9. A printing machine comprising a horizontal platen and ink pad disposed in elevated position with respect to the platen, a type carrying carriage suspended above the platen and pad to swing into and out of engagement with the pad and to vertically move into and out of engagement with the platen, and gearing mechanism engageable with the carriage and adapted to be actuated to swing and vertically move the said carriage.

10. A printing machine comprising a frame, a shaft journaled in a frame, guide rods swingingly suspended from the frame, a carriage slidably mounted on the guide rod and adapted to swing therewith, and means mounted on the shaft and on the said carriage to swing the said carriage and the said guide rods and to slide the carriage on the guide rod when the said shaft is actuated.

11. A printing machine comprising a frame, a platen, guide rods suspended from the frame, to laterally swing above the said platen, an inking device, a type carrying carriage slidably mounted on the guide rods and adapted to swing therewith into and out of engagement alternately with the said platen and inking device.

12. A printing machine comprising a frame, parallel guide rods suspended from the frame, a type carriage slidably mounted on the guide rods, an operating shaft, a rack carried by the carriage, gear elements mounted on the shaft and engageable with the rack to actuate the carriage when the said shaft is actuated, and means mounted on the carriage and the said gear elements to retain the carriage and gear elements in relative operative position while the said gear elements are in engagement with the said rack.

13. A printing machine comprising a frame, guide rods suspended from the frame, a carriage mounted on the guide rods to permit reciprocatory movement of the carriage, the said carriage having a rack member, toothed segments engageable with the rack member, a drive shaft supporting the toothed segment to impart motion thereto when the shaft is actuated, the said segment carrying pins and means formed on the carriage to receive the pins for retaining the carriage and said segments in relative operative engagement for imparting a swinging and oscillating movement to the said carriage when the shaft is actuated.

14. A printing machine comprising a frame, a carriage suspended from the

frame for lateral swinging and vertical sliding movement, gears mounted to engage the carriage for swinging the same, pins attached to the gears, the said carriage having arcuate grooves, each open at one end to receive the said pins, whereby the said pins are movable in the grooves during swinging movement of the said carriage.

15. A printing machine comprising a frame, a carriage suspended from the frame for lateral swinging and vertical sliding movement, gears mounted to engage the carriage for swinging the same, pins attached to the gears, the said carriage having arcuate grooves, each open at one end to receive the said pins, whereby the said pins are movable in the grooves during swinging movement of the said carriage, and means mounted on the frame and engageable with the carriage to maintain the latter in vertical position when the said pins are out of registration with the said grooves.

16. The combination with a type carrying carriage mounted for vertical reciprocatory movement and lateral oscillatory movement, and gears to impart movement to the said carriage, of disks mounted on the carriage and provided with arcuate grooves having open ends in the edges of the disks, and laterally projecting pins carried by said gears and adapted to register with the said arcuate grooves in the disk by passing through the said open ends thereof, during movement of the said carriage and gears, whereby the said carriage will be maintained in proper position with respect to the said gears during movement thereof.

17. The combination with a type carrying carriage mounted for vertical reciprocatory movement and lateral oscillatory movement and gearing engageable with the said carriage to impart the said movement thereto when the gearing is actuated, of disks carried by the carriage and each provided with an annular flange having a portion cut out to form a gap, the said carriage having parallel bars, the lower ends of the bars being adapted to be received in the said gap in the disk to form the edges of arcuate grooves in the said disks, and pins carried by the said gearing and adapted to be received in the said grooves to maintain the said carriage in operative position with respect to the said gearing during movement thereof.

In testimony whereof I affix my signature.

FRANK S. WEISE.
